CLAIM

The ornamental design for a handle for a surgical instrument as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of an embodiment of a claimed design;

FIG. 2 is a bottom perspective view of the embodiment in FIG. 1;

FIG. 3 is a front view of the embodiment in FIG. 1;

FIG. 4 is a back view of the embodiment in FIG. 1;

FIG. 5 is a right side view of the embodiment in FIG. 1;

FIG. 6 is a left side view of the embodiment in FIG. 1;

FIG. 7 is a top view of the embodiment in FIG. 1;

FIG. 8 is a bottom view of the embodiment in FIG. 1;

FIG. 9 is a top perspective view of an embodiment of the claimed design;

FIG. 10 is a bottom perspective view of the embodiment in FIG. 9;

FIG. 11 is a front view of the embodiment in FIG. 9;

FIG. 12 is a back view of the embodiment in FIG. 9;

FIG. 13 is a right side view of the embodiment in FIG. 9;

FIG. 14 is a left side view of the embodiment in FIG. 9;

FIG. 15 is a top view of the embodiment in FIG. 9; and,

FIG. 16 is a bottom view of the embodiment in FIG. 9.

The figures illustrate a handle for a surgical instrument. Features of the article that are not shown are disclaimed. Additionally, any features shown in broken lines are for illustrative purposes only and form no part of the claimed design.
